UNITED STATES PATENT OFFICE.

WILLIAM THOMAS JOHNSON, OF BEAVER FALLS, PENNSYLVANIA, ASSIGNOR TO THE
MAYER CHINA COMPANY, OF BEAVER FALLS, PENNSYLVANIA, A CORPORATION
OF PENNSYLVANIA.

DESIGN FOR AN ARTICLE OF MANUFACTURE.

47,731.

Specification for Design.

Patented Aug. 17, 1915.

Application filed May 1, 1915. Serial No. 25,295. Term of patent 7 years.

To all whom it may concern:

Be it known that I, WILLIAM THOMAS JOHNSON, a subject of the King of Great Britain, residing at Beaver Falls, in the county of Beaver and State of Pennsylvania, have invented a new, original, and ornamental Design for an Article of Manufacture, of which the following is a specification, reference being had to the accompanying drawing, forming part thereof.

The figure is a plan view of a portion of my design to be applied to an article of manufacture.

While I have shown the various parts of the design produced in black, it is to be understood that I may reproduce the design in various colors, or use different colors in different parts of the design.

I claim:

The ornamental design for an article of manufacture as shown and described.

WILLIAM THOMAS JOHNSON.

In presence of—

JOSEPH MAYER,
E. MAY GIRVAN.
